UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING, ASSOCIATING, AND FOLDING MACHINE.

1,269,040.

Specification of Letters Patent. Patented June 11, 1918.

Application filed August 5, 1916. Serial No. 113,368.

To all whom it may concern:

Be it known that I, HOWARD M. BARBER, a citizen of the United States, and resident of Stonington, in the county of New London 5 and State of Connecticut, have invented a new and useful Improvement in Sheet Collecting, Associating, and Folding Machines, of which the following is a specification.

The object of this invention is to provide 10 novel means for associating extra sheets fed from different sources of sheet supply, such, for instance, as cover and insert sheets, with a collected group of sheets fed from another source of supply, means preferably being 15 employed for stitching the so associated sheets together and for folding the same.

A practical embodiment of my invention is represented in the accompanying drawings, in which

20 Figures 1 and 1^a represent, in longitudinal vertical section taken just inside the near side frame, so much of a sheet collecting, associating and folding machine as includes my invention,

25 Figs. 2 and 2^a represent the same in longitudinal vertical central section,

Figs. 3 and 3^a represent the geared connection between the several parts, and

30 Figs. 4 and 4^a represent a longitudinal vertical section taken just inside the far side frame.

1 designates a source of extra sheet supply, such, for instance, as an insert sheet supply. 2 designates a different source of extra sheet 35 supply, such, for instance as a cover sheet supply.

These sources 1 and 2 are herein shown as feed tables, the table 1 being provided with a movable sheet stop 3 and the table 2 with a 40 movable sheet stop 4.

The rotary cutters 5, 6, mounted on suitable shafts 7, 8, are arranged to cut a single web or a plurality of superimposed webs which pass between the rolls 9, 10, into 45 sheets, which sheets are passed downwardly between guides 11, 12, and between the rotary coacting carriers 13, 14, mounted on shafts 15, 16, respectively. These carriers are arranged to collect the sheets in groups.

50 In the present instance, the rotary carrier 14 is provided with a set of grippers 17 and the rotary carrier 13 is provided with a set of grippers 18. A rotary associating carrier 19 mounted on the shaft 20 is herein shown as being provided with an odd number of sets of grippers 21, three for instance.

A rotary transfer carrier 22 mounted on the shaft 23 is arranged to feed the extra sheets successively from the different sources of sheet supply 1 and 2 into position to be 60 associated on the associating carrier 19 with a group of sheets fed from the rotary carrier 13. This rotary transfer carrier 22 is shown as having an even number of sets of grippers 24, 25, two for instance, the said set 65 of grippers 24 being arranged to take the sheets from the source of sheet supply 1 and the grippers 25 being arranged to take the sheets from the source of sheet supply 2.

A stitcher table 26 is arranged to receive 70 the associated sheets, where they are stitched transversely of their travel by the coacting parts 27, 28, of two or more stitchers. A movable stop 29 at the outer end of the stitcher table 26 is arranged in position to 75 engage the advance edges of the associated sheets and hold them momentarily in position for the stitching operation.

Coacting rotary carriers 30, 31, mounted on their respective shafts 32, 33, are provided; the carrier 30 having a set of grippers 80 34 arranged to take the stitched associated sheets from the stitcher table 26 and also having a folding blade 35 arranged to coact with the folding jaws 36 on the rotary carrier 31 for imparting a transverse fold to the associated sheets along their transversely stitched line.

Endless carriers 37, 38, serve to carry the 90 associated sheets onto and off from the stitcher table 26 and endless carriers 39, 40, serve to carry the product from the rotary carrier 31 to a suitable delivery 41, 42.

The train of gears, designated by 43 to 66 inclusive, is operative to drive the parts at 95 the proper relative speeds. In the present instance, the rotary carriers 13 and 14 are run at the same surface speed; the carrier 19 at a slightly greater surface speed; and the carrier 22 at the same surface speed as 100 the carrier 19.

The carriers 30 and 31 rotate one revolution to one revolution of the rotary carrier 14.

A switch 67 is located at the entrance end 105 of the stitcher table 26, which switch is operated from a cam 68 on the shaft 32 of the rotary carrier 30, through the connection 69.

A movable cam 70, for opening the grippers 21 at the proper intervals to receive 110 the sheet fed from the extra source of sheet supply 1, is controlled by a cam 71 on the

shaft 15 of the rotary carrier 13 through the connection 72.

A movable cam 73, for releasing the grippers 21 of the associating carrier at the proper intervals to deliver the associated sheets onto the stitcher table 26, is controlled by a cam 74 on the shaft 15 of the rotary carrier 13 through the connection 75.

Coacting folding mechanism on the carriers 30 and 31 is of the well known floating blade and jaw type, in which the cam 76 controls the blade 35 and the cams 77, 78, and 79, control the folding jaws 36.

The grippers 34 are opened to release the associated sheets at the time of folding, by the stationary cam 80.

A fixed cam 81 controls the grippers 17 of the rotary carrier 14 and fixed cams 82, 83, control the grippers 18 at the points where they receive the group of sheets from the rotary carrier 13 and transfer the same to the rotary carrier 19, respectively.

A fixed cam 84 controls the grippers 21 at the point where they receive the group of sheets from the carrier 13.

The grippers 24 of the rotary carrier 22 are tumbler operated, their tumbler 85 being controlled by the pins 86, 87. The grippers 25 on the rotary carrier 22 are also tumbler operated, their tumbler 88 being controlled by the pins 89, 90.

The movement of the sheet stop 3 is controlled by the cam 91 arranged to engage the sheet stop roller 92. The movement of the sheet stop 4 is controlled by the cam 93 arranged to engage the sheet stop roller 94. The movement of the sheet stop 29 is controlled by the cam 95 which is arranged to engage the sheet stop roller 96. A fixed cam 97 opens the grippers 24 to permit the sheets fed from the extra source of sheet supply 1 to be fed to the grippers 21 of the associating carrier 19. A fixed cam 98 opens the grippers 25 to release the sheets fed from the extra source of sheet supply 2 for association with the group of sheets and the extra sheet fed from the source 1.

The grippers 34 of the rotary carrier 30 are tumbler operated, their tumbler 102 being controlled by pins 103, 104.

Positively driven rollers 99, 100, bear against the surface of the rotary carrier 19 to hold the sheets in register thereon when the grippers are open and a positively driven roller 101 engages the surface of the rotary carrier 22 to hold the sheets in register thereon when their grippers are open.

The mechanism is herein shown as arranged for association with a group of sheets of an insert sheet fed from the source of sheet supply 1 and a cover sheet fed from the different source of sheet supply 2, with the insert on one side of the group of sheets and the cover on the other side thereof.

The rolls 9, 10, may feed one or more webs to the rotary cutters 5, 6, where the sheets are severed from the web or webs and fed through the guides, 11, 12, to the sheet collecting carriers 13, 14. These carriers are, in the present instance, arranged to collect two sheets or two groups of superimposed sheets, according to whether one or more webs be handled and feed the same to the sheet associating carrier 19 on top of an insert sheet.

The rotary carrier 22 is arranged to take an insert sheet from the source of supply 1 and feed it to the associating carrier 19. This rotary carrier is arranged to take a cover sheet from the source of sheet supply and feed it into position to be associated with the insert sheet and group of sheets, on top of the group of sheets. These associated sheets are then fed forwardly onto the stitcher table 26, the switch 67 being thrown into position to insure the passage of the insert sheet with the other sheets onto the said table.

When these associated sheets reach the stop 29, the sheets are stitched transversely of their travel. The stop is then raised and the advance edges of the sheets are grasped by the set of grippers 34 on the rotary sheet carrier 30. The associated stitched sheets are then folded off along their stitched line transverse of their travel onto the rotary sheet carrier 31 and are delivered therefrom to the delivery mechanism 41, 42.

It is obvious that the rotary sheet carriers 13, 14, can handle single sheets or a plurality of superimposed sheets fed from the rotary cutters 5, 6, and it is also obvious that the rotary sheet carrier 22 can feed one sheet or a plurality of superimposed sheets from each of the different sources of sheet supply 1 and 2 without departing from the spirit and scope of my invention.

It is evident that changes may be resorted to in the form, construction and arrangement of the several parts without departing from the spirit and scope of my invention; hence I do not wish to limit myself strictly to the structure herein set forth, but

What I claim is:

1. Means for collecting a group of sheets, means for associating extra sheets fed from different sources with said group of sheets and a common means for feeding the extra sheets successively to the associating means.

2. Means for collecting a group of sheets, means for associating extra sheets fed from different sources with said group of sheets, a common means for feeding the extra sheets successively to the associating means, and means for stitching the so associated sheets together and delivering the same.

3. Means for collecting a group of sheets, means for associating extra sheets fed from

different sources with said group of sheets, a common means for feeding the extra sheets successively to the associating means, and means for folding the so associated sheets together and delivering the same.

4. Means for collecting a group of sheets, means for associating extra sheets fed from different sources with said group of sheets, a common means for feeding the extra sheets successively to the associating means, and means for stitching and folding the so associated sheets together, and delivering the same.

15 the same.
16 5. Rotary carriers arranged to collect a
17 group of sheets, a rotary carrier arranged
18 to associate thereon extra sheets fed from
19 different sources with the collected group
20 of sheets, and a rotary carrier arranged to
21 feed the extra sheets to the sheet associat-
22 ing carrier.

20 *ing carrier.* 6. Rotary carriers arranged to collect a group of sheets, a rotary carrier arranged to associate extra sheets fed from different sources with the group of sheets, a
25 rotary carrier arranged to feed the extra sheets to the sheet associating carrier, and means for stitching the so associated sheets together and delivering the same.

7. Rotary carriers arranged to collect a
30 group of sheets, a rotary carrier arranged to
associate thereon extra sheets fed from
different sources with the collected group
of sheets, a rotary carrier arranged to feed
the extra sheets to the sheet associating car-
35 rier, and means for folding the so associated
sheets together and delivering the same.

8. Rotary carriers arranged to collect a group of sheets, a rotary carrier arranged to associate extra sheets fed from different 40 sources with the group of sheets, a rotary carrier arranged to feed the extra sheets to the sheet associating carrier, and means for stitching and folding the so associated sheets together and delivering the same.

45 9. Rotary carriers arranged to collect a group of sheets, a rotary carrier arranged to associate extra sheets fed from different sources with the group of sheets, and a rotary carrier arranged to feed the extra sheets successively to the sheet associating carrier.

10. Rotary carriers arranged to collect a group of sheets, a rotary carrier arranged to associate extra sheets fed from different sources with the group of sheets, a rotary carrier arranged to feed the extra sheets successively to the sheet associating carrier, and means for stitching the so associated sheets together and delivering the

60 same.

11. Rotary carriers arranged to collect a group of sheets, a rotary carrier arranged to associate extra sheets fed from different sources with the group of sheets, a rotary carrier arranged to feed the extra sheets

65

successively to the sheet associating carrier, and means for folding the so associated sheets together and delivering the same.

12. Rotary carriers arranged to collect a group of sheets, a rotary carrier arranged to associate extra sheets fed from different sources with the group of sheets, a rotary carrier arranged to feed the extra sheets successively to the sheet associating carrier, and means for stitching and folding the so associated sheets together and delivering the same. 70 75

13. Rotary carriers arranged to collect a group of sheets, a rotary carrier arranged to associate extra sheets fed from different sources with the group of sheets, and a rotary carrier arranged to feed the extra sheets to the sheet associating carrier, the parts being so timed that the sheet associating carrier will first take an extra sheet from one source, then the group of sheets, and finally associate therewith an extra sheet from another source. 85

14. Rotary carriers arranged to collect a group of sheets, a rotary carrier arranged to associate extra sheets fed from different sources with the group of sheets, a rotary carrier arranged to feed the extra sheets to the sheet associating carrier, the parts being so timed that the sheet associating carrier will first take an extra sheet from one source, then the group of sheets and finally associate therewith an extra sheet from another source, and means for stitching the so associated sheets together and delivering the same. 90 95 100

15. Rotary carriers arranged to collect a group of sheets, a rotary carrier arranged to associate extra sheets fed from different sources with the group of sheets, a rotary carrier arranged to feed the extra sheets to the sheet associating carrier, the parts being so timed that the sheet associating carrier will first take an extra sheet from one source, then the group of sheets and finally associate therewith an extra sheet from another source, and means for folding the so associated sheets together and delivering the same. 105 110

16. Rotary carriers arranged to collect a group of sheets, a rotary carrier arranged to associate extra sheets fed from different sources with the group of sheets, a rotary carrier arranged to feed the extra sheets to the sheet associating carrier, the parts being so timed that the sheet associating carrier will first take an extra sheet from one source, then the group of sheets and finally associate therewith an extra sheet from another source, and means for stitching and folding the so associated sheets together and delivering the same. 123

17. Means for collecting a group of sheets, a rotary carrier arranged to associate extra sheets fed from different sources with the 130

- group of sheets, and a rotary carrier arranged to take the extra sheets at different points on the carrier and feed them to the associating carrier at different times.
- 5 18. Means for collecting a group of sheets, a rotary carrier arranged to associate extra sheets fed from different sources with the group of sheets, a rotary carrier arranged to take the extra sheets at different points 70
10 on the carrier and feed them to the associating carrier at different times, and means for stitching the so associated sheets together and delivering the same.
19. Means for collecting a group of sheets, 75
15 a rotary carrier arranged to associate extra sheets fed from different sources with the group of sheets, a rotary carrier arranged to take the extra sheets at different points on the carrier and feed them to the associating
20 carrier at different times, and means for folding the so associated sheets together and 80
delivering the same.
20. Means for collecting a group of sheets, a rotary carrier arranged to associate extra 85
25 sheets fed from different sources with the group of sheets, a rotary carrier arranged to take the extra sheets at different points on the carrier and feed them to the associating carrier at different times, and means
30 for stitching and folding the so associated sheets together and delivering the same. 90
21. Means for collecting a group of sheets, a rotary carrier having an odd number of 95
surfaces upon which extra sheets fed from 35 different sources are associated with each group of sheets, and a rotary carrier having an even number of surfaces on which the extra sheets are taken in succession and from which they are fed at different times to the 40 associating carrier to be associated with each group of sheets. 100
22. Means for collecting a group of sheets, a rotary carrier having an odd number of 105
surfaces upon which extra sheets fed from 45 different sources are associated with each group of sheets, a rotary carrier having an even number of surfaces on which the extra sheets are taken in succession and from which they are fed at different times to the 50 associating carrier to be associated with each group of sheets, and means for stitching the so associated sheets together and delivering the same. 110
23. Means for collecting a group of sheets, 55 a rotary carrier having an odd number of surfaces upon which extra sheets fed from different sources are associated with each group of sheets, a rotary carrier having an even number of surfaces on which the extra
60 sheets are taken in succession and from which they are fed at different times to the associating carrier to be associated with each group of sheets, and means for folding the so associated sheets together and delivering the same. 115
24. Means for collecting a group of sheets, a rotary carrier having an odd number of surfaces upon which extra sheets fed from different sources are associated with each group of sheets, a rotary carrier having an even number of surfaces on which the extra sheets are taken in succession and from which they are fed at different times to the associating carrier to be associated with each group of sheets, and means for stitching and folding the so associated sheets together and delivering the same. 120
25. A source of main sheet supply, different sources of extra sheet supply, a rotary sheet associating carrier, means for collecting a group of main sheets and for feeding the group to the associating carrier, and a common means arranged to take the extra sheets successively from the different sources of extra sheet supply and transfer them 125
75 successively to the associating carrier to be combined with said group of sheets. 130
26. A source of main sheet supply, different sources of extra sheet supply, a rotary sheet associating carrier, means for collecting a group of main sheets and for feeding the group to the associating carrier, a common means arranged to take the extra sheets successively from the different sources of extra sheet supply and transfer them 135
80 successively to the associating carrier to be combined with said group of sheets. 140
27. A source of main sheet supply, different sources of extra sheet supply, a rotary sheet associating carrier, means for collecting a group of main sheets and for feeding the group to the associating carrier, a common means arranged to take the extra sheets 145
90 successively from the different sources of extra sheet supply and transfer them successively to the associating carrier to be combined with said group of sheets, and means for stitching the so associated sheets together and delivering the same. 150
28. A source of main sheet supply, different sources of extra sheet supply, a rotary sheet associating carrier, means for collecting a group of main sheets and for feeding the group to the associating carrier, a common means arranged to take the extra sheets 155
95 successively from the different sources of extra sheet supply and transfer them successively to the associating carrier to be combined with said group of sheets, and means for folding the so associated sheets together and delivering the same. 160
29. A source of main sheet supply, different sources of extra sheet supply, a rotary sheet associating carrier, means for collecting a group of main sheets and feeding the group of sheets to the associating carrier, and a single rotary carrier arranged to take 165
100 the same. 170

the extra sheets successively from the different sources of extra sheet supply and transfer them successively to the associating carrier to be combined with the said 5 group of sheets.

30. A source of main sheet supply, different sources of extra sheet supply, a rotary sheet associating carrier, means for collecting a group of main sheets and feeding the 10 group of sheets to the associating carrier, a single rotary carrier arranged to take the extra sheets successively from the different sources of extra sheet supply and transfer them successively to the associating carrier 15 to be combined with the said group of sheets, and means for stitching the so associated sheets together and delivering the same.

31. A source of main sheet supply, different sources of extra sheet supply, a rotary 20 sheet associating carrier, means for collecting a group of main sheets and feeding the group of sheets to the associating carrier, a single rotary carrier arranged to take the

extra sheets successively from the different sources of extra sheet supply and transfer 25 them successively to the associating carrier to be combined with the said group of sheets, and means for folding the so associated sheets together and delivering the same.

32. A source of main sheet supply, different sources of extra sheet supply, a rotary sheet associating carrier, means for collecting a group of main sheets and feeding the group of sheets to the associating carrier, a single rotary carrier arranged to take the 30 extra sheets successively from the different sources of extra sheet supply and transfer them successively to the associating carrier 35 to be combined with the said group of sheets, and means for stitching and folding the so 40 associated sheets together and delivering the same.

In testimony that I claim the foregoing as my invention, I have signed my name this third day of August 1916.

HOWARD M. BARBER.
